UNITED STATES PATENT OFFICE.

WILLIS POLK, OF SAN FRANCISCO, CALIFORNIA, ASSIGNOR OF ONE-HALF TO SOLOMON LEVY, OF SAN FRANCISCO, CALIFORNIA.

ARCHITECTURAL STRUCTURE.

1,334,634.

Specification of Letters Patent. Patented Mar. 23, 1920.

Application filed June 6, 1918. Serial No. 238,415.

To all whom it may concern:

Be it known that I, WILLIS POLK, a citizen of the United States, and a resident of the city and county of San Francisco, State 5 of California, have made a new and useful Invention—to wit, Improvements in Architectural Structures; and I do hereby declare the following to be a full, clear, concise, and exact description of the same.

10 The invention relates particularly to the novel construction and arrangement of a building structure, with the object of obtaining the maximum amount of natural illumination throughout the interior of the 15 structure. Other objects and advantages will appear as this description progresses.

In this specification and the annexed drawings, the invention is illustrated in the form considered to be the best, but it is to 20 be understood that the said invention is not limited to such forms because it may be embodied in other forms, and it is also to be understood that in and by the claims following the description it is desired to cover the 25 invention in whatever form it may be embodied.

In the accompanying two sheets of drawings:

Figure 1 is a perspective view of the facade of a building constructed in accordance with this invention.

Fig. 2 is an enlarged fragmentary detail in front elevation of the same.

Fig. 3 is a fragmentary side elevation of 35 the same.

Fig. 4 is a plan view of the same.

In detail the construction illustrated in the drawings includes the conventional foundation structure with the usual side 40 walls 1 with the interior supporting columns 2 resting upon foundation piers and distributed throughout the structure as conventionally required to support the floor weight. These supporting columns are 45 joined by transverse girders, trusses and supports in the usual manner to sustain the various floors 3 of the structure supported by the usual floor beams 4. In the drawings reinforced concrete construction is indicated, 50 but it will become manifest as this description progresses that any type of architectural structure may be modified to include this invention.

While the drawings show only the facade 55 of the building, it is evident that also the

rear and the sides may be similarly constructed to attain the maximum amount of interior illumination. It is the conventional practice to carry the wall of the buildings clear to the property line 5. In the present 60 instance the supporting means consisting of the columns 2 are set back from the property line a distance of two feet more or less, to the line 6, the transverse support consisting of the girder 7 resting upon the 65 column 2. To this girder 7 is attached the supporting brackets 8 to support the mullion frame work 9 fixed thereto perpendicular with the property line 5. Within this mullion frame are mounted suitably glazed 70 sash frames 10, some or all of which may be pivoted as at 11 to be opened for ventilation and cleaning. The glass front makes the discovery of fire, starting within the building, more easy and likely before it is 75 beyond control. The tilting sashes also make the fighting of fire more efficient and the water loss less incident thereto, because the effort may be concentrated more directly on the source because of its greater visibility. Other advantages are sufficiently manifest.

A distinguishing characteristic of this invention is that the usual exterior window sills which in tall buildings are of considerable depth, and extend outside of the glazed sash plane, are in the present instance interior of the structure, and form the ledge 12. This ledge 12 is elevated above the level of the floor 3 and forms a very convenient 85 utility within the room for the display of merchandise or table space, that would not be available in buildings of the conventional type of architecture, in which the window sill is exterior to the plane of the window 90 as previously described.

The ceiling 13 is finished in the usual manner leaving a space between the floor 3 and the ceiling 13 for the cross beams 4 and the concealment of pipe and electric 100 wiring in the usual manner. Adjacent to the facade wall the ceiling rises to the ledge 12 giving an angular space within which the brackets 8 are located, which space or offset in the ceiling is a primary element in 105 this invention, in that it elevates the point of inlet of illumination from the normal point A to the point B. An angle of light such as B—C entering at B at an angle of approximately forty-five degrees will penetrate 110

trate farther into the interior of the room than it would if entering at the point A, which is the point of entrance in the conventional type of building. The comparison 5 in Fig. 3 is even favorable to the old type in that a certain area of the glazed sash is sacrificed to the shadow caused by the overhanging wall above it, because of the sash being set back of the property line 5. Subtracting the width of the mullions and window sashes from the total area of the facade of the building close to ninety-eight 10 per cent. of glass is presented for the penetration of light, rendering this class of building particularly adapted to what is known as loft buildings, usually partitioned 15 into large rooms or inclosures, in which daylight is a prime consideration for the display of merchandise or for mechanical activities. A facade of this glazed type can 20 be rendered very attractive by inserting tinted or muffled glass as at the shaded portions 14, which also obscure the off-set portions of the transverse girder 7 and the 25 brackets 8. The same treatment in vertical lines as at 16 in colored glass, matching the 30 trimming of the building, satisfies the artistic sense and establishes a just relation and true correspondence in the architectural design.

Having thus described my invention, what I claim and desire to secure by Letters Patent is:

1. An architectural structure including a 35 facade, the greater area of which is penetrable by light; and a ceiling spaced back from said facade and joined thereto by an angular upward extension projecting upwardly above the ceiling to form a pocket 40 to receive light through the facade.

2. An architectural structure including a 45 glazed facade; and a horizontal ceiling terminating at a distance spaced from the facade and having an upwardly projecting vertical offset rising from the terminal edge of the ceiling to a point adjacent said facade to form a light receiving pocket.

3. An architectural structure including a 50 glazed facade; supports spaced back from said facade; ceilings supported by and terminating at said supports and having upwardly projecting vertical off-sets extending from said supports to a point adjacent said facade.

55 4. An architectural structure including vertical supporting means; a glazed facade spaced outward from and supported by sup-

ports; a ceiling supported by means and spaced back from said facade; a ledge extending inward from said facade above the 60 ceiling level; and a horizontal girder interposed between said supporting means and said facade for supporting said ledge.

5. An architectural structure including vertical supporting columns; a transverse 65 girder spanning said columns; a ledge extending forward from near the top of said girder; and a ceiling extending rearward from near the bottom of said girder; and a vertical glazed facade set perpendicular to 70 said ledge and spaced outward from said girder in advance of said ledge.

6. An architectural structure including vertical supporting means; a facade in advance of said supporting means and having 75 its greater area penetrable by light; floors spaced backward from said facade; a ledge; and brackets interposed between said supporting means and said facade for supporting said ledge above the ceiling level.

7. An architectural structure including a 80 mullion frame facade the greater area of which is penetrable by light and having tilting sashes therein; and superposed floors spaced back from said facade and each 85 having an upward and outward off-set ledge joining said facade above the level of said floors, said sashes tilttable within said off-set ledge portions.

8. An architectural structure including a 90 glazed facade, the greater area of which is penetrable by light, and a floor spaced back from said facade and having an upward and outward off-set ledge extending 95 to the facade above the level of the floor.

9. An architectural structure including a 100 glazed facade, the greater area of which is penetrable by light, superposed floors and corresponding ceilings spaced back from said facade, a substantially horizontal ledge 105 above the level of each floor and extending between the facade and the adjacent edge of the floor, and a substantially vertical member between the ledge and the adjacent ceiling below said floor, the floor surface 110 extending to said vertical member.

In testimony whereof, I have hereunto set my hand at San Francisco, California, this 20th day of May, 1918.

WILLIS POLK.

In presence of—

LINCOLN V. JOHNSON,
A. J. HENRY.
